(57) **CLAIM**

The ornamental design for “pneumatic drill”, as shown and described.

DESCRIPTION

FIG. 1 is a perspective view of “pneumatic drill” showing our new design thereof;

FIG. 2 is a right side elevational view;

FIG. 3 is a top plan view thereof;

FIG. 4 is a front side elevational view;

FIG. 5 is a bottom plan view thereof;

FIG. 6 is a left side elevational view;

FIG. 7 is a rear side elevational view; and,

FIG. 8 is a perspective view thereof shown in condition of use.

The broken line showing of environmental structure is for illustrative purposes only and forms no part of the claimed design.
